J. SIEGEL

CORSET

Filed Jan. 10, 1921

Inventor
Joseph Siegel

W. H. Whitney, Attorney

Attorneys

UNITED STATES PATENT OFFICE.

JOSEPH SIEGEL, OF DETROIT, MICHIGAN, ASSIGNOR TO AMERICAN LADY CORSET COMPANY, OF DETROIT, MICHIGAN, A CORPORATION OF MICHIGAN.

CORSET.

Application filed January 10, 1921. Serial No. 486,035.

To all whom it may concern:

Be it known that I, JOSEPH SIEGEL, a citizen of the United States of America, residing at Detroit, in the county of Wayne and 5 State of Michigan, have invented certain new and useful Improvements in Corsets, of which the following is a specification, reference being had therein to the accompanying drawings.

10 This invention relates to corsets and consists in certain features of construction hereinafter fully set forth and illustrated in the accompanying drawing, wherein;

15 Figure 1 is a front view of the upper portion of the improved corset;

Figure 2 is a similar view with certain parts broken away;

Figure 3 shows the garment in side elevation in use;

20 In these views the reference character A designates the improved corset and B indicates detachably connected vertical edges thereof, which are shown at the front of the garment, but for the purpose of the invention

25 may have any desired circumferential location. The connecting means similarly may have various forms, but as illustrated comprises metallic pin and loop connections C. These connections are carried by a pair

30 of busks D which are concealed in the garment in the usual manner, in proximity to the edges B. At the top of the garment, portions E thereof located at each side of the edges B, have the nature of upstanding

35 projections, this effect resulting from extending apertures F downwardly from the upper edge of the garment in a symmetrical relation to the edges B. Closures for said apertures are formed by a pair of flaps G stitched

40 respectively to the remote edges of the apertures F as indicated at G', and suitable fastenings, as for example, the hook and eye members H, provide for a quick detachable connection between said flaps. It is pre-

45 ferred to arrange the connected edges of the flaps G somewhat to one side of the main adjoining vertical edges B of the garment, as clearly shown in Figure 1, and to extend the busks D upwardly some distance into the 50 portions E, as indicated in dash lines in said figure.

In the practice heretofore followed in corset construction, the upper end portions of the steels or busks marginal to detachably connected edges of the garment have lacked

sufficient freedom to flexibly conform to the body of the wearer, responsive to a forward bending movement, or responsive to any movement of the body, subjecting said end portions to an increased bending stress. 60 Consequently, under such circumstances, an uncomfortable pressure has been exerted abdominally upon the body by said busks or steels. The present invention eliminates this discomfort by avoiding any lateral connection between the portions E of the garment, engaged by the upper end portions of the busks D, and the body of the garment. Thus said portions E and the busk end portions are not restrained from outward flexing but will yield freely under any increased body pressure. 70

It is to be observed that the flaps G extend across the apertures F so as to provide a closure for said apertures and maintain a 75 substantially continuous marginal line at the top of the garment.

What I claim as my invention is:

1. A waist-embracing garment having detachably connected vertical edges and having openings formed in its top portion at each side of said edges providing upstanding portions marginal to said edges, members secured to said garment at the remote edges of said openings and closing the latter, and means for detachably securing said members together in rear of one of said upstanding portions. 80

2. A waist-embracing garment having detachably connected vertical edges and having openings formed in its top portion at each side of said edges providing upstanding portions marginal to said edges, members secured directly to said garment at the remote edges of said openings and extending in rear of said upstanding portions to close said openings, and means for detachably securing said members together. 90

3. A waist-embracing garment having detachably connected vertical edges and having openings formed in its top portion at each side of said edges providing upstanding portions marginal to said edges, members secured to said garment at the remote edges of said openings and closing the latter, one of said members extending beyond the vertical edges of said garment, and means for detachably securing said members together in rear of one of said upstanding portions. 100

110

4. A waist-embracing garment having vertical edges and having openings formed in its top portion at each side of said edges providing upstanding portions marginal to 20
5 said edges, members secured to said garment at the remote edges of said openings and closing the latter, busks concealed in 25
said garment and extending upwardly into 30
10 said upstanding portions, means carried by 35
said busks for detachably securing the vertical edges of said garment together, and means independent of the securing means
aforesaid for securing said members together.
- 15 5. A waist-embracing garment having detachably connected vertical edges and having openings formed in its top portion at each side of said edges providing upstanding portions marginal to said edges, rela-

tively wide flaps secured to said garment at 20
the remote edges of said openings, said flaps extending from below the lower edges of 25
said openings and terminating even with the upper edges of said garment, and means
for securing said members together.

6. A waist-embracing garment having detachably connected vertical edges and having openings formed in its top portion at each side of said edges providing upstanding portions marginal to said edges, and a 30
flap permanently secured to one of the remote edges of said openings, and means detachably engageable with said flap carried by the other of said remote edges, the said 35
upstanding portions lying outside of said flap.

In testimony whereof I affix my signature.
JOSEPH SIEGEL.
